2,122,481

METHOD OF MAKING A TUBULAR PRODUCT

Albert S. Lynch, Beaver, Pa., assignor to Jones & Laughlin Steel Corporation, Pittsburgh, Pa., a corporation of Pennsylvania

Application December 2, 1935, Serial No. 52,481

3 Claims. (Cl. 29—156)

This invention relates broadly to tubular products and the manufacture thereof, and more particularly to the formation of tubular products by upsetting. It relates still more particularly to a method of forming a pipe section having an integral coupling portion and to a novel pipe section of such character.

It has been proposed to make pipe in sections with integral coupling portions on the respective sections by upsetting the pipe ends to form the integral coupling portions. Pipe of this character is especially well adapted for use as drill pipe for drilling wells. In my copending application Serial No. 739,122, filed August 9, 1934, there is disclosed and claimed a method of forming a tubular product of the character above mentioned and a drill pipe section having certain novel features.

A disadvantage of pipe sections having integral upset coupling portions as heretofore produced is the constriction of the bore of the section caused by upsetting. It is not possible in a single upsetting operation in which the metal is caused to flow only outwardly, or away from the pipe axis, to increase the wall thickness over about 30 per cent. An attempt to do so results in a grain structure in the metal which is unsatisfactory, and a product thus produced is of no practical value. On the other hand, it is possible in a single upsetting operation in which the metal is caused or allowed to flow inwardly, or toward the pipe axis, to increase the wall thickness up to or slightly over 150 per cent. and still produce a strong commercially satisfactory product having the proper grain structure.

Consequently, in the production of pipe of the character here concerned with it is not feasible to upset externally only, as a considerable number of upsetting operations and intermediate reheatings would be necessary which would increase the cost of the pipe out of all proportion to its value. Therefore, internal upsetting is resorted to. A satisfactory pipe section having an integral upset coupling portion can be produced in this way by a comparatively small number of upsetting operations, as, for example, one, two or three. It is preferable to use either two or three upsetting steps, but this compares favorably with the number of steps which would be required if an attempt should be made to form the section by external upsetting only. At least four, and probably five or six, upsetting steps with intermediate reheatings would be necessary to form the section by external upsetting only.

Inward upsetting therefore has an important advantage in reduction of the cost of producing the upset pipe. This advantage is so important that it is from the commercial standpoint necessary to produce pipe sections having integral coupling portions by inward upsetting. Sections produced by outward upsetting only could never be sold at a price even approaching their cost, so that this method is commercially worthless. However, inward upsetting has the disadvantage above mentioned of constriction of the bore. This is highly undesirable as it seriously impedes the flow of fluid through the pipe and greatly reduces the efficiency of the pipe.

Moreover, in upsetting pipe a mandrel is employed which during the upsetting extends within the pipe and assists in shaping the upset metal. In order to enable withdrawal of the mandrel without damage to the work the mandrel is made tapered. Ordinarily the mandrel forms a part of the upsetting tool and passes into the pipe to be upset ahead of the portion of the tool which contacts the end of the pipe to perform the upsetting operation, the mandrel being tapered to minimum diameter at its forward extremity. The mandrel is designed so that the upset product will have the desired wall thickness at the portion of the mandrel of relatively great diameter, resulting in constriction of the bore toward the forward extremity of the mandrel. This constriction is in many cases highly undesirable and disadvantageous, not only because it impedes fluid flow through the upset pipe, but also because, due to the conditions imposed in upsetting, the wall thickness of the upset pipe at the point of minimum diameter of the mandrel may be considerably greater than desired.

For example, it is not possible by any commercially practicable method heretofore employed to form a pipe section having an integral upset coupling portion having the desired internal and external shape and the desired wall thickness at all points along the tapered mandrel. It has not been possible to produce commercially drill pipe with integral upset coupling portions and of uniform bore, which is and has for years been recognized as being the most highly desirable form of drill pipe.

The problems above mentioned have long been recognized but no satisfactory solution thereto has heretofore been found. An example of a theoretical suggestion for the formation of uniform bore integral joint upset drill pipe is the upsetting of the extremities of a drill pipe section externally only so as to avoid constriction of the

bore. However, as explained above, this proposal is not commercially feasible. Pipe produced according to this suggestion could never be marketed. Moreover, I understand it to be the fact that pipe has never been made in accordance with such suggestion either commercially or non-commercially. Such suggestion simply represents a theoretical paper scheme. This suggestion is of interest, however, as showing recognition of the problem which applicant has solved.

In the formation of pipe of the character in question in which the wall thickness of the upset portion is to be at least 30 per cent. greater than the wall thickness of the pipe it is necessary in commercial operation, as above explained, to upset the metal inwardly or toward the axis of the pipe. I prefer to utilize the method of upsetting disclosed in my said application, first inwardly upsetting the metal in either one or two steps and then outwardly upsetting. However, the ultimate upset product has a constricted bore and a wall portion of unnecessarily great thickness. In certain cases such constricted bore and thick wall portion are not particularly undesirable but in other cases they are highly undesirable, and it is a purpose of the present invention to obviate the disadvantages mentioned.

I preferably upset an end of a pipe section whereby to increase the wall thickness and reduce the internal diameter thereof and thereafter reshape the interior of at least the part of the upset portion which is of least internal diameter to reduce the restrictive effect imposed thereby. I preferably accomplish the reshaping by removing material from the interior of the upset portion. Such removal is preferably effected by a machining operation, and I find it especially desirable and convenient to bore out at least part of the upset portion. In this manner I am able to render the bore of the upset portion of the section of substantially constant diameter for at least a substantial distance longitudinally of the section, and the bore of the upset portion may be rendered of substantially constant diameter and, if desired, of the same diameter as the bore of the non-upset portion of the section. In one preferred method of carrying out the invention presently to be described I form in a commercially satisfactory manner drill pipe having a substantially uniform bore throughout. So far as I am aware, this is the first time that upset integral joint uniform bore drill pipe has ever been produced either commercially or non-commercially. Heretofore when uniform bore drill pipe has been specified separate couplings have been used which are relatively expensive, far more difficult to assemble and much less satisfactory in use.

Pipe made by upsetting and then boring out or similarly removing a portion of the material from the interior of the upset portion may readily be identified by the machined surface at at least a portion of the bore. Such machined surface is also of advantage in reducing the friction losses suffered by fluid passing through the pipe. While the friction loss in any one section of pipe may not be great, when it is considered that a large number of sections are coupled together in use the friction loss is an important factor.

Other details, objects and advantages of the invention will become apparent as the following description of certain present preferred embodiments thereof and certain present preferred methods of practicing the same proceeds.

In the accompanying drawing I have shown certain present preferred embodiments of the in-

vention and have illustrated certain present preferred methods of practicing the same, in which

Figure 1 is a central longitudinal cross-sectional view through a portion of an upset blank used in the formation of a pipe section;

Figure 2 is a similar view of the blank shown in Figure 1 but with a portion of the interior thereof reshaped; and

Figures 3 and 4 are views corresponding respectively to Figures 1 and 2 showing a different form of structure.

Referring now more particularly to the drawing, Figures 1 and 2 illustrate the formation of an integral coupling portion for the box or female end of a pipe section while Figures 3 and 4 illustrate the formation of an integral coupling portion for the pin or male end of the section. The method used in either case is substantially the same.

Referring first to the form of Figures 1 and 2, there is provided a length of pipe of suitable characteristics and whose initial wall thickness may be as shown at the left-hand extremity of Figure 1. The end of the pipe length or section is preferably heated for a suitable distance from its extremity, as well known in the art, and is then subjected to one or more upsetting operations which may be, and preferably are, substantially the same as or similar to the upsetting operations described and illustrated in my said copending application. The end of the section or blank after completion of the upsetting is shown in Figure 1 and is designated generally by reference numeral 2. The external diameter is increased to the desired extent as shown at 3 and the internal diameter is controlled as desired at the point 4 which coincides with the portion of relatively great diameter of the tapered length of the mandrel used in the upsetting step. The point corresponding with the extremity of such tapered length of the mandrel is indicated at 5. The diameter of the bore of the upset section is materially less at the point 5 than at the point 4, although this may be undesirable in the finished product due to the restrictive effect, the relatively great amount of material embodied in the section and the increased weight thereof.

I reshape the interior of the upset portion of the section, as explained above, preferably by boring, and the bored-out section is shown in Figure 2. The material included between the chain line 6 and the inner surface of the section has been removed, rendering the bore of the entire section substantially uniform from end to end. I thus produce integral joint uniform bore drill pipe by a method which is practicable from the commercial standpoint. As stated above, although uniform bore integral joint drill pipe has been sought for many years, it has never before, so far as I am aware, been produced commercially or even non-commercially.

Figures 3 and 4 are exactly analogous to Figures 1 and 2 showing the male end of the section. Parts of Figures 3 and 4 corresponding respectively with parts of Figures 1 and 2 are designated by like reference numerals each having a prime affixed.

The upset pipe as shown in Figures 2 and 4 may be subjected to desired after-operations such as heat treatment, threading and finishing. However, the pipe formed as above described is of the desired shape and no further modification in respect of its shape either internally or externally is necessary.

While I have shown and described certain present preferred embodiments of the invention and certain present preferred methods of practicing the same, it is to be distinctly understood that the invention is not limited thereto but may be otherwise variously embodied and practiced within the scope of the following claims.

I claim:

1. A method of making an upset integral joint 10 drill pipe section of substantially uniform bore, comprising heating a generally tubular blank, upsetting an end portion of the blank both internally and externally whereby to decrease its internal diameter and increase its external diameter, such upsetting operation entailing relatively few upsetting and reheating operations as compared with those which would be necessary if the blank were upset outwardly only, increasing the external diameter of the blank by such upsetting sufficiently that substantially the amount of metal necessary for formation of an integral pipe joint lies outside a cylinder defined by the original internal diameter of the blank, and reshaping the blank to enlarge the reduced internal 25 diameter thereof at said upset portion to substantially the internal diameter of the non-upset portion of the blank.
2. A method of making an upset integral joint 30 drill pipe section of substantially uniform bore, comprising heating a generally tubular blank, upsetting an end portion of the blank both internally and externally whereby to decrease its internal diameter and increase its external diameter, such upsetting operation entailing relative-

ly few upsetting and reheating operations as compared with those which would be necessary if the blank were upset outwardly only, increasing the external diameter of the blank by such upsetting sufficiently that substantially the amount of metal necessary for formation of an integral pipe joint lies outside a cylinder defined by the original internal diameter of the blank, and removing material from the interior of the blank at said upset portion to enlarge the reduced 10 internal diameter thereof at said portion to substantially the internal diameter of the non-upset portion of the blank.

3. A method of making an upset integral joint 15 drill pipe section of substantially uniform bore, comprising heating a generally tubular blank, upsetting an end portion of the blank both internally and externally whereby to decrease its internal diameter and increase its external diameter, such upsetting operation entailing relatively 20 few upsetting and reheating operations as compared with those which would be necessary if the blank were upset outwardly only, increasing the external diameter of the blank by such upsetting sufficiently that substantially the amount of 25 metal necessary for formation of an integral pipe joint lies outside a cylinder defined by the original internal diameter of the blank, and boring out of the blank at said upset portion to enlarge the reduced internal diameter thereof at said portion to substantially the internal diameter of 30 the non-upset portion of the blank.
